DESIGN FOR A COMBINED SCORING BOARD AND TRUMP-CARD INDICATOR

Richard Gerald Pavey, Seven Kings, England

Application August 12, 1942, Serial No. 107,887
In Great Britain March 23, 1942

Term of patent 14 years

To all whom it may concern:

Be it known that I, Richard Gerald Pavey, a subject of the King of Great Britain, residing at 5 Holmwood Road, Seven Kings, in the county of Essex, England, have invented a new, original, and ornamental Design for a Combined Scoring Board and Trump-Card Indicator, of which the following is a specification, reference being had to the accompanying drawing, forming part thereof.

In the drawing, Figure 1 is a plan view of a

combined scoring board and trump-card indicator, showing my new design, and Figure 2 is a cross-section on the line II—II of Figure 1.

The board is substantially flat, with a raised pointer in the center, the groups of shaded small circles representing depressions or holes.

I claim:

The ornamental design for a combined scoring board and trump-card indicator, as shown, and described.

RICHARD GERALD PAVEY.
